ION SOURCE

Clarence M. Turner, Stony Brook, N. Y., assignor
to the United States of America as represented
by the United States Atomic Energy Commis-
sion

Application January 28, 1953, Serial No. 333,709

13 Claims. (Cl. 250—41.9)

1

This invention is a continuation-in-part of the invention disclosed in application Serial No. 574,156, filed January 23, 1945, now abandoned, and relates to gaseous electric discharge apparatus and especially to an electric arc discharge apparatus capable of producing in quantity a substantially continuous supply of gaseous ions under vacuum. More particularly, the electric arc discharge apparatus of the present invention is designed primarily for generating substantial quantities of metal ions, as are required, for example, in apparatus for separating or concentrating the isotopes of metals such as copper 63 and 65, cobalt 59 and 60, or uranium 234, 235, 237 and 238 by appropriate selective operation upon ions of different atomic mass in an ion beam. The separation of such isotopes is important to provide quantities of a selected isotope for research, medicinal or industrial purposes such as radiography. This may be accomplished in accordance with this invention by bombarding a vapor containing the several isotopes of the metal with the electrons of an arc discharge established between nonfilamentary electrodes one of which is thermionically emissive and maintained so by the alternate electron bombardment of this electrode and another thermionically emissive electrode that results when these electrodes are connected to an alternating voltage.

One type of isotope separating or ion-classifying apparatus in which the ion source of the present invention may be advantageously used may be found described and claimed in a Patent 2,606,291 issued August 5, 1952, to Robert R. Wilson. This ion-classifying apparatus may consist essentially of an evacuated and sealed chamber, that may be cylindrical and of predetermined proportions, for supporting the ion source and its ion accelerating electrodes at an end thereof, and for supporting equipotential bunching electrodes at a predetermined distance spaced from said accelerating electrodes and maintained at the steady state potential to provide a field free space intermediate the accelerating electrode and the buncher structure for the flow therethrough of the accelerated ionized particles. An alternating radio frequency potential of small amplitude and preferably saw-tooth wave form is applied to the bunching electrode for periodically impressing increments of velocity both positive and negative upon the ionized particles passing therethrough to cause these particles to bunch together in accordance with their mass. A radiofrequency alternating potential is applied also to a deflecting electrode that is sup-

2

ported within the chamber at a distance spaced from said buncher electrodes to provide a substantial field free space of definite length immediately following and adjoining said bunch electrodes. This alternating potential is synchronized with the buncher potential to deflect the grouped ions enriched with the desired isotope of the ionized material into a collecting pocket or cup positioned at or adjacent the end of said chamber.

That the operation of an ionic mass separating device such as that described above (or other types employing cooperating electric and magnetic fields for classifying ions) may be effectively employed on a production basis it is essential that the ion source utilized in the device be capable of continuous operation for long periods without serious deterioration of the arc electrodes, to supply the ions necessary for large scale separation of the isotopes of the ionized material.

Prior to the present invention one effective procedure for producing ions of a metal has been to bombard the vapors of the metal or of suitable volatile salts of the metal by the accelerated electrons of an arc discharge established between a filamentary cathode and an anode. In these procedures, particularly the procedures where metallic vapors are generated by depositing controlled quantities of the metal on the anode, the filament becomes contaminated with the source metal since it is exposed directly to the anode where the source metal is being vaporized. This contamination has in certain instances caused the filament to burn out after an operating time of only two hours.

Furthermore, when a filamentary cathode is used with direct current heating, the effect of the arc current flowing through the filament is to make one end hotter and the other end cooler, since in one end the filament and arc current are in the same direction while in the other end they are in opposite directions. This increase in heating of one end causes the filament to burn out more quickly than if the heating were uniform. Attempts to eliminate this unequal heating by utilizing an alternating current, for example, for heating the filament, have been unsuccessful because the alternating current produced large fluctuations in the ion output.

It has been discovered from observing the results of arc operation on the filament that conduction or direct heating by the filament current is basically unstable, since the corrosion, or evaporation of the filament can never be uni-

form, thus the cross-section of the filament at one point will decrease in excess of the decrease in cross-section of other points on the filament, with the result that the region of smaller cross-section becomes increasingly hotter further reducing the cross-section until the filament burns out. Furthermore, it has been found that a considerable amount of power must be supplied to the filament to heat it to desired emission temperature. When direct heating of the cathode is used, as in the filament type of arc ion sources, the power required represents many hundreds of amperes preferably, direct current, at the relative low potential of a volt or two. Suitable low voltage sources capable of supplying this current magnitude present power supply problems that are avoided in this invention.

In the course of investigations undertaken to extend the life of the electrodes of an arc discharge capable of producing gaseous ions of a material that is normally solid and vaporizable under vacuum only with the application of high temperatures, it was discovered that a satisfactory operating time for these arc electrodes, greater by a factor of three, than that obtained formerly, could be realized by utilizing an arc cathode heated to electron emissive temperatures by the bombardment thereof of accelerated electrons emitted from a filamentary cathode. It was found that a platform cathode could thus be utilized and heated uniformly by the electron bombardment from a heated filament so that the platform could be positioned intermediate the anode and filament to protect or shield the filamentary cathode from the vapors within the arc region, thus reducing the contamination of filament by these vapors. It will be observed, of course, that the unequal heating of the filament by the arc and heating current is eliminated through the employment of such an indirectly heated arc cathode.

Ion generating apparatus developed as a result of this discovery and of a type similar to that described and claimed in a copending application, S. N. 671,981, filed May 24, 1946, was found also to have other concomitant advantages. It was discovered that the use of a platform arc cathode as distinguished from a filamentary arc cathode provided a large emitting area that enabled the arc to be started more easily, and further because of the increase in emission, resulting from both the larger area and higher temperature, it was found that the arc could be made to run steadily at almost any voltage above five volts, by varying the power input to the arc cathode.

Notwithstanding the satisfactory operation and concomitant advantages possessed by this arc source of ions employing the indirectly heated cathode, it was found that this source failed to avoid entirely the disadvantages attendant the use of a heated filament, e. g. it was found that after prolonged operation the arc cathode would eventually allow sufficient vapor to get to the heating filament to establish an arc between this filament and the main cathode. Furthermore, although alternating current could be used to heat the filament the necessity for a low voltage power source capable of supplying continuously currents of several hundred amperes was not avoided.

When these disadvantages were noted to persist, further research leading to the present invention was undertaken. It occurred to me that the necessity for continuing the supply of

heating current to the filament could be dispensed with if the arc cathode could be heated by using an alternating current between the filament and the arc cathode. Attempts to so heat the cathode by means of alternating current were initially unsuccessful however because the electron bombardment of the filament on the reverse cycle was sufficient to melt the filament. After the idea of utilizing two somewhat massive non-filamentary cathode structures for alternate bombardment with electrons was hit upon, and found to avoid the previously encountered difficulties; it appeared desirable for reasons of greater stability and longer life of the heating element, to attempt the development of an indirectly heated arc cathode which would prevent, at least for a prolonged period of operation, the penetration of the isotope metal vapors to the heating element; accordingly it was proposed to make the arc cathode completely contain or enclose the intermediate or secondary cathode and to be so thick as to be substantially impenetrable.

Thus the arc electrodes of the ion source of the present invention were developed and comprise specifically an arc cathode constructed of a large rod of tungsten, for example, provided with an axial hole in one end thereof for containing a second intermediate cathode also preferably of tungsten. A loop filament surrounds the arc cathode for producing the electron bombardment for initially heating the arc cathode to electron emissive temperature, after which the filament is turned off and the heating maintained by connecting between the hollow thimble-like arc cathode and the rod a source of alternating potential.

It was observed that, as a result of its smaller mass, the intermediate rod cathode was heated to a higher temperature than the outer and larger arc cathode upon equal electron bombardment. It was discovered that this inequality in heating could be eliminated by having the source of A. C. feeding the cathodes controlled by thyratrons, or other gaseous discharge device in such a way that the power fed into the thimble and that fed into the rod could be independently controlled.

It will be apparent from the foregoing therefore that this invention has for its purpose the attainment of the following objects:

First, to provide an improved non-filamentary source of electrons for an arc discharge device;

Second, to provide an improved non-filamentary source of electrons having a large emitting area for supplying a uniform and copious supply of electrons to an electric arc discharge device thereby enabling the arc to be started more easily;

Third, to provide an improved electron source for use in an arc discharge device capable of continuous operation for long periods in the presence of corrosive vapors through which the arc discharge is established;

Fourth, to provide a non-filamentary source of electrons for an arc discharge device that is operable on alternating currents at moderate voltage magnitudes to avoid the disadvantages concomitant with the electron sources operable only from low voltage sources capable of supplying direct currents of high amperage;

Fifth, to provide a source of electrons for an arc discharge device wherein the arc cathode, or electron emissive electrode employed in the arc discharge, is heated to electron emissive tem-

perature as a result of mutual and alternate electron bombardment produced between it and another electrode spaced from the arc cathode and shielded from the region of the arc discharge by being contained within said arc cathode;

Sixth, to provide a control means in a source of electrons for an arc discharge device which will permit an independent control of the emission temperature of each of two spaced electrodes that are maintained electron emissive by mutual and alternate electron bombardment on alternate half cycles of an alternating potential supplied to these electrodes.

A further and more specific object of this invention is to provide an efficient and copious arc source of ions of a material that is normally solid and vaporizable under vacuum only with the application of high temperatures that employs an improved electron source for the arc that is operable on alternating current and of increased life.

Further objects and many of the attendant advantages of this invention will be appreciated more fully as the same become better understood by reference to the following detailed description of a preferred embodiment, when taken with the accompanying sheets of drawing wherein:

Figure 1 is a detailed elevational view of a preferred embodiment of the present invention shown largely in cross-section the section being taken on lines I—I of Figure 2;

Figure 2 is a cross-sectional end view taken on lines II—II of Figure 1; and

Figure 3 is a wiring diagram illustrating the operation of the present invention.

Referring now to the drawings and more particularly to Figures 1 and 2, the ion source illustrated is to be positioned within one end of an evacuated chamber housing the ion utilization apparatus, preferably by being supported within the insulated tubing 10 of quartz, porcelain, or other suitable refractory insulating material, to insulate the ion source unit from the evacuated chamber so that it may be maintained at a high positive potential, of the order of 20,000 volts, relative to an accelerating electrode 11 which is indicated only schematically, to provide the electric field for withdrawing the ions from the region of the arc and accelerating these ions to a high velocity. More specifically, the ion source electrodes are shown supported and sealed in a water cooled metallic end plate 12 in insulated relation therewith, and this end plate is provided with a circular groove 12' into which the ceramic supporting cylinder 10 is inserted and sealed by means of the gasket ring 13 adapted to be compressed by an annular packing gland, not shown, to maintain the air tight integrity of the chamber.

The end plate 12 is shown provided with a centrally disposed opening 14 drilled therein for supporting the refractory insulating bushing 15 and the concentric and spaced apart metallic tubes 16 and 17 that are partitioned longitudinally for a substantial distance of their length to provide a supply and return conduit for the circulation of a cooling fluid for cooling a chuck 18 that is shown inserted into the ends of these tubes and a cathode 20 which it supports. The chuck 18 has a central opening 19 for receiving the thimble arc cathode 20 of tungsten or other suitable electron emissive material which is held in place by radially directed set screws of which 21 is representative. As an aid in the support of the insulating bushing 15 and the concentric

tubes 16 and 17 a cylindrical metallic sleeve 22 is shown welded to the outside surface of the end plate 12 concentric with the drilled opening 14. The opening in the free end of this sleeve 22 is enlarged and tap threaded to receive the packing gland 23 for forcing a gasket material 24 into intimate contact with the insulating bushing to provide an airtight seal at the end of the bushing that projects through the end plate and to the high pressure end of this sleeve.

In the interests of simplicity of illustration no seal is provided for the surface between the insulating bushing 15 and the outer metallic tube 16 although it is apparent that in the event an airtight fit between the contacting surfaces of these members cannot be maintained otherwise, a suitable sealing gland may be easily installed.

An intermediate auxiliary or second rod cathode 25, also of tungsten, is shown supported to extend within an opening 27 drilled in the end of the main arc cathode 20 preferably by means of the electrolytic drilling process in spaced and insulated relation with the arc cathode and its supporting structure. Accordingly a chuck 26 for supporting the rod 25 is shown supported coaxially within the tube 17 through a flanged insulated bushing 28 and metallic sleeve 29. More precisely, a pair of coaxial and spaced apart tubes 30 and 31 support the chuck 26 within the sleeve 29, to provide conduits for circulating cooling fluid through the space 32 intermediate the tubes to cool the cathode rod 25 where it is supported in the chuck to prevent warping of this rod at its support. One effective way of providing for the flow of the cooling fluid through the space 32 is to have the annular space formed by the coaxial tubes partitioned circumferentially by means of a pair of diametrically spaced wires having a diameter equal to the radial spacing of the tubes and of a length substantially equal to the tube lengths so that they will extend longitudinally down the space 32 to terminate just short of the end of the tubes. Accordingly the tubes 30 and 31 are shown provided with entrant and exit tubes 33 and 34 respectively for this cooling fluid.

Inasmuch as the space between the rod 25 and thimble cathode 20 must be evacuated if heating by electron bombardment is to be effective, the chuck 18 is shown provided with a plurality of radial openings 35 that extend from this space to the exterior surface of the arc cathode to communicate with the chamber of the ion utilization apparatus that is connected to a suitable pumping apparatus for continuous evacuation. Furthermore, the high pressure ends of each pair of tubes 16, 17 and 30, 31 are shown provided with packing glands 36, 37 for sealing the ends of each surface of tubes 16 and 30, respectively, to the flanged insulated bushing 28, and the metallic sleeve 29. Furthermore the high pressure ends of the tubes 30 and 31 are sealed off as at 38. To complete the insulation between thimble and rod cathode, and to secure an inner airtight seal of the space between the metallic sleeve 29, and the insulated bushing 28, as well as the space between the chuck 18 and insulated bushing 28, the chuck and flanged bushing are each shown provided with circular recesses 41 and 42 formed in their end surface for receiving sealing rings 43, 44 and opposite ends of a glass cylindrical insulating sleeve 40. The insulated bushing 28 is provided with a flange 45 against which the packing gland nut 36' is forced to

seal the glass sleeve 40 between the opposite surfaces containing the recesses 41 and 42 by compressing the seal rings 43 and 44, against the end surface of the glass sleeve and the back wall of their respective recesses.

As illustrated the anode comprises a platform 46 consisting of several rods of tungsten, for example, placed side by side and welded to a pair of parallel supporting rods 47, also of tungsten, and suitably supported by the end plate 12. More specifically the supporting rods 47 are each supported by their respective lead-in conductors 48 which extend through sealed openings in the end plate. A starting cathode is provided consisting of a tungsten wire 50 encircling the thimble cathode 20 and spaced radially a short distance from it, and at one side of the region of the anode wherein the arc is established. Opposite ends of the filamentary starting cathode 50 are supported by the lead-in conductors 51 which are sealed and insulated in their passage through the end plate 12, by a bushing 39 of suitable refractory insulating material and gland 49, shown in cross-section in Figure 1, as being similar in construction to that employed for sealing and insulating the tube 16 in the passage through the end plate 12. It being understood that other insulated seals may be employed and also that an additional seal for each bushing 39 and conductor 51 may be provided if necessary to maintain the chamber airtight. The lead-in conductors 51 for the filament starting cathode 50 and the lead-in electrodes 48 for the platform anode are each provided with a suitable squirt tube such as 52 for example, which extends concentrically with the lead-in electrodes to provide a circulating path for a cooling fluid for removing the heat from the cathode or the anode as in the case of the lead-in conductors 48, at its support to prevent warping of either the cathode or the anode.

To feed metal to the arc as needed, an appropriate supply device has been provided. By way of example, one such device may comprise a feed tube or duct 53 extending through the tube 54 which is sealed and supported in the end plate 12 by means of the packing gland 55, said duct being shown terminating at a point at the edge of and slightly above the platform 46. A wire or ribbon of metal 56 which may be copper, uranium or cobalt for example, may be advanced continuously or in successive steps as desired, through this tube 53 to the upper surface of the platform. A cooling tube 57 is shown extending through the tube 54 in contact with the feed tube 53 for the circulation therethrough of a cooling fluid for preventing the wire from becoming heated in the feed tube to deleteriously effect the feeding operation thereof.

It will be appreciated that various supporting and feeding structures to be mounted in the end plate 12 may include suitable insulating sealing or packing means (not shown) where needed, in accordance with the usual practice for vacuum type apparatus. Although mechanical wire-advancing means, e. g. including a reel and motor driven rollers drawing the wire from the reel and pushing it through the tube 53 (such parts being insulated and enclosed in a communicating evacuated housing if desired) may be employed in some cases to feed the wire continuously. Satisfactory results can be obtained also by utilizing a timing device set to operate the feeding mechanism intermittently at the desired time intervals.

Referring now to Figure 3 of the drawings there is shown in the wiring diagram one convenient way of connecting an alternating voltage to the two cathodes to produce the alternate electron bombardment on opposite half-cycles thereof that includes also a means whereby the power input into each of the cathodes may be independently controlled. It will be clear that the cathodes 20 and 25 are connected to the A. C. supply source through a variable autotransformer 60, for example, to provide a control of the magnitude of the applied alternating voltage. As shown, the rod cathode 25 is connected directly to the A. C. supply whereas the thimble cathode 20 is connected to the A. C. supply through a pair of gaseous discharge tubes 61 and 62, one of which is inverted relative to the other to provide a current conductive path on alternate cycles. The discharge tube 62 is merely a rectifier tube connected to provide a conductive path for flow of electrons from the rod cathode 25 to the thimble arc cathode 20 during the portion of the cycle of the alternating voltage applied thereto, that the thimble is positive relative to the rod. The ballast resistor 63 is provided merely to limit the current to a safe value. The gaseous discharge tube 61 is grid controlled and may be rendered conductive at selective points in the cycle of the alternating voltage when the rod 25 is positive relative to the thimble 20 by adjusting the phase of the grid and plate potential for example, to control the heating of the rod 25 independently of the heating of the thimble 20. A suitable phase control circuit consisting of an adjustable series resistance 65, and adjustable reactance 66 is provided and is shown energized from a secondary 67 of a transformer 68 in series with a center-tapped resistor 69 connected to the cathode of the tube 61. The grid 70 of the tube 61 is connected into the phase control circuit at the junction of the series connected resistor 65 and reactor 66 through a resistance 71 which is provided merely to limit the grid current to a safe value after the tube fires. This series resistor 71 may of course be omitted if both impedances 65 and 66 are at all times large enough to limit the grid current. The phase of the grid voltage and time of firing of the tube 61 is of course controlled by changing the magnitude of the resistor 65 or of the reactor 66 in accordance with well-known practice.

In operating the apparatus a switch S_1 is first closed to connect the filament of the starting cathode 50 to a source of heating voltage 72 to heat the filament to an electron emissive temperature. Switches S_2 and S_3 are then closed for connecting the starting cathode 50 and the thimble cathode 20 in circuit with the voltage supply 73 so that the thimble 20 is at a positive electrical potential relative to the filament to provide the accelerating voltage for the thermionic emission of the cathode 50 to cause the electrons thereof to bombard the thimble to heat the thimble to electron emissive temperatures. After the thimble 20 is thus heated to a desired electron emissive temperature, switch S_4 may be closed to connect the thimble cathode 20 and rod cathode 25 to the source of alternating voltage the amplitude of which is controlled through the variable autotransformer 60, to cause the electrons of the thimble to bombard the rod to heat it also to an electron emissive temperature, after which the emission of each the thimble 20 and rod 25 may be sustained by the mutual bom-

bardment by electrons of the thimble and rod on alternate half cycles. The switches S_1 and S_3 are then opened to remove the source of heater voltage from the filament and to disconnect the filament from the source of electron accelerating voltage. Switch S_5 may then be closed, in the event this connection has not been previously established, to connect the arc voltage between thimble arc cathode 20 and the platform anode 46. The establishment of this arc running to the anode upon which has been deposited controlled amounts of the isotope source metal, results in the vaporization and subsequent ionization of this metal by electron bombardment of the vapors thus produced. The ions thus formed are withdrawn and accelerated in the form of a beam through a suitable accelerating electrode schematically indicated by the cylindrical shell 11 by means of the high negative potential 73 to which this electrode is connected.

In view of the foregoing description, it will now be apparent that what is illustrated and described is but a preferred embodiment of this invention that has been constructed and successfully operated wherein the main arc cathode comprises a tungsten thimble made by electrolytically drilling a hole $\frac{1}{4}$ inch in diameter and $1\frac{1}{2}$ inch deep centered in a tungsten rod $\frac{1}{2}$ inch in diameter by 2 inches long; and wherein the intermediate cathode comprises a 150-mil rod, also of tungsten which projects into this hole to within $\frac{1}{8}$ inch of the end and serves as the heater for the arc cathode in the manner described above. It is conceived that this structure illustrated may be modified in substantial measure and applied to other uses without departing, however, from the spirit of and scope of this invention as defined in the subjoined set of claims.

I claim:

1. In an arc source for producing ions an electronic discharge device comprising an anode, a first and second thermionically emissive electrode, starting means for initially heating at least one of said electrodes to an electron emissive temperature, means for applying an alternating voltage between said first and second electrodes to cause the electrons emitted by an electrode rendered electron emissive by said first named means to bombard the other of said electrodes to heat said other electrode for sustaining the emission of both of said electrodes by mutual electron bombardment thereof on alternate half cycles of said alternating voltage and independently of said first named means, means for producing an arc discharge between one of said electrodes and said anode and means for introducing into the region of said arc discharge a vapor of the material to be ionized.

2. The combination defined by claim 1 above characterized further by the addition thereto of means for controlling the thermionic emission of said electrodes relative to each other comprising means for controlling the magnitude of said alternating voltage and means for selecting the point in the half cycle of said alternating voltage that the electrons emitted by said first one of said electrodes are made to bombard the second one of said electrodes, while maintaining throughout the complete other half cycle of alternating voltage the bombardment of said first electrode by the electrons emitted by said second electrode.

3. An electric discharge device comprising a main hollow cathode, an auxiliary cathode in-

sulatingly supported within the main electrode, a gaseous medium disposed adjacent said main cathode, means including a filamentary element surrounding said main and auxiliary cathode for rendering said main cathodes electron emissive, said auxiliary cathode being shielded from said filamentary element by the main cathode means including a source of alternating voltage connected between said cathodes for producing an electric discharge running from said main to said auxiliary cathode to heat said auxiliary cathode to an electron emissive temperature, whereby the emission of said main cathode will be maintained by the bombardment of electrons from said auxiliary cathode on alternate half cycles of said alternating current independently of said filamentary means, and means for directing electrons emitted from said main cathode into said medium, whereby to ionize said medium.

4. The combination defined in claim 3 above characterized further by the addition thereto of means in circuit with said auxiliary cathode for selecting the portion of the alternating voltage cycle that the electrons of said main cathode bombard said auxiliary cathode while maintaining the bombardment of said main cathode by the electrons of said auxiliary cathode throughout said half cycle of said alternating voltage that the main cathode is positive relative to said auxiliary cathode.

5. An electric discharge device comprising a first cathode, an anode, a second cathode disposed intermediate said first cathode and said anode, means for rendering one of said cathodes electron emissive, means for applying an alternating voltage between said first cathode and said second cathode whereby electrons emitted from the cathode rendered electron emissive bombard the other of said cathodes to raise said other cathode to an electron emissive temperature, means for producing a vapor of the material to be ionized in the region disposed between said second cathode and said anode and means for producing an arc discharge between said second cathode and said anode through said vapor containing region to ionize said vapor.

6. An electric discharge device comprising an evacuated sealed chamber, means for introducing a gaseous medium to a region within said chamber, a hollow main cathode supported adjacent said region, an auxiliary cathode completely contained within said hollow cathode to be shielded thereby from said gaseous medium, means for initially rendering one of said cathodes electron emissive, alternating current means for sustaining said electron emission of both said cathodes independently of said first named means by the mutual electron bombardment thereof, and means for directing into said region electrons emitted by said main cathode whereby gas in said region is ionized.

7. The combination defined in claim 6 above characterized further by the addition thereto of means for controlling the electron bombardment of said cathodes relative to each other to control the degree of heating thereof.

8. An electric discharge device comprising an evacuated sealed chamber, means for introducing a gaseous medium into a region within said chamber, a hollow rod arc cathode, an auxiliary rod cathode disposed therein, a filamentary cathode spaced radially from and surrounding said hollow rod cathode, means including a source of electric power for raising the temperature of said filamentary cathode to render it electron

emissive, means including a voltage source for bombarding said hollow rod cathode with electrons emitted from said filamentary cathode, whereby said hollow rod cathode is rendered electron emissive, means including a source of alternating voltage connected between said hollow rod arc cathode and said auxiliary rod cathode for producing an electric discharge from said arc cathode to said auxiliary cathode whereby said auxiliary cathode is rendered electron emissive for sustaining the electron emission of both said arc cathode and auxiliary cathode independently of said filament by the mutual electron bombardment thereof on alternate half cycles of said alternating voltage, and means for directing electrons emitted by said arc cathode into said region to ionize said gaseous medium.

9. An electric discharge device comprising a pair of thermionically emissive electrodes, means for initiating thermionic emission from at least one of said electrodes, means including a source of alternating voltage between said electrodes for causing the electrons emitted by one electrode to bombard the other of said electrodes to heat said other electrode and sustain by mutual electron bombardment the emission of both of said electrodes, and a grid controlled gaseous electric discharge device series connected between one of said electrodes and said source for controlling the portion of the half cycle of electron bombardment of one of said electrodes, whereby the power input to said one of said electrodes may be controlled independently of said other electrode.

10. In an arc source for producing ions, an electronic discharge device comprising first and second electrodes, means for initiating thermionic emission from at least one of said electrodes and means for sustaining the emission thereof by mutual electron bombardment of said electrodes,

means supporting one of said electrodes rendered electron emissive within a region containing a gaseous medium, means for directing electrons from one said electrode into said region whereby said gas in said region is ionized, and means for controlling the electron bombardment of said electrodes relative to each other to control the degree of heating thereof.

11. An electronic discharge device comprising a pair of thermionically emissive electrodes, a gaseous medium disposed adjacent one of said electrodes, means including a source of alternating voltage connected between said electrodes for rendering said electrodes electronic emissive, means for directing electrons emitted by said one electrode into said gaseous medium whereby said gas is ionized, and means for controlling the thermionic emission temperature of said electrodes relative to each other.

12. An ion generating device comprising a sealed chamber, a relatively massive cathode within said chamber, an auxiliary cathode within said main cathode and completely shielded thereby, means for initially rendering one of said cathodes electron emissive, alternating current means connected to said cathodes for sustaining said electron emission independently of said first means by the mutual electronic bombardment thereof, an anode spaced from said main cathode and means for striking an arc discharge between said arc cathode and said anode.

13. The structure of claim 12 including means for introducing a material to be vaporized and ionized within said sealed chamber and said anode being in the form of a platform positioned to shield said main cathode from said material as it vaporizes.
